UNITED STATES PATENT OFFICE.

JAMES MCKINSEY JOHNS, OF GLENMORE, GEORGIA.

AUTOMATIC FAN.

SPECIFICATION forming part of Letters Patent No. 337,587, dated March 9, 1886.

Application filed October 1, 1884. Serial No. 144,437. (No model.)

To all whom it may concern:

Be it known that I, JAMES MCKINSEY JOHNS, a citizen of the United States, residing at Glenmore, in the county of Ware and 5 State of Georgia, have invented certain new and useful Improvements in Automatic Fans, of which the following is a description.

This invention relates to that class of devices used to circulate air in houses by automatic action of fans; and it has for its object to fan the air fast or slow, high or low, and to locate the fan on any convenient structure or article of furniture where a current of air is desired.

15 To this end my invention consists in the construction and combination of parts forming an automatic fan hereinafter described and claimed, reference being had to the accompanying drawings, in which—

20 Figure 1 is a front elevation of my invention at rest in an upright position, and Fig. 2 is a side elevation of the same in position for service.

A represents a fan adjustably secured upon 25 a pendulum-rod, B, which is hung in a box, C, to be swung to and fro by a crank, D, operated by clock-work F, and connected with the upper end of the rod by a link, E. The fan A is secured to the rod B by a binding- 30 strap, G, which may be set with screws to hold by friction to the rod at any point along the same.

H H are two other fans firmly secured at 35 the ends of arms I, which arms are pivoted at J to the rod B, to spread the fans, as shown in Fig. 2, or to bring them together, as shown in dotted lines. These fans H are connected with the central fan, A, by means of bracing-links K, so that if the central fan be raised it 40 spreads and raises the side fans, and the friction-strap G, holding to the rod B, temporarily secures all the fans at any height required.

The box L, containing the clock-work which

operates the fan, is hung to rock upon pivots M in a bracket, N, which is in turn hinged at 45 Q in a base-piece, O, which is provided with holes and screws P, to secure it to any article of furniture or to any fixture of a house. This base may be fixed either on the top or on the side of any sufficiently stable object to support it, and the bracket is adapted to be swung therefrom into a horizontal position by means of its hinge Q, and the box C rocks on its pivots M, to permit the fans to hang downward. The pivots M are set-screws adapted 55 to bind the box to the bracket in any position.

When the fans are set high up on the pendulum-rod, their stroke is shortened and quickened, and vice versa. The clock-work may 60 be run by a spring, a weight, or any other motive power.

What I claim as my invention, and desire to secure by Letters Patent, is—

1. The combination, with clock-work, a 65 pendulum-rod caused to oscillate thereby, and a central fan adjustably fixed on the pendulum-rod, of two side fans hung by arms pivoted to the pendulum-rod and two brace-links connecting the side fans with the central 70 fan, substantially as shown and described.

2. The combination, with a fan hung upon a pendulum-rod and clock-work to cause the said rod to oscillate, of a box to hold the clock-work, the double-branched or bifurcated 75 bracket-arms N, having pivotal screws M M, sustaining the box between said arms, and a base-piece supporting the bracket-arm by a hinge, the base-piece being provided with screw-holes and screws, substantially as shown 80 and described.

JAMES MCKINSEY JOHNS.
